UNITED STATES PATENT OFFICE

EMANUEL BAUMGARTEN, OF WASHINGTON, DISTRICT OF COLUMBIA, ASSIGNOR TO
VELVET PAD AND INK CO., A CORPORATION OF DELAWARE

RESILIENT STAMP PAD

Application filed December 16, 1927. Serial No. 240,477.

The invention relates to stamp pads for inking purposes, and has for its objects to provide an improved stamp pad of resilient construction and inherent advantages. The 5 principal object of the invention is to provide a resilient stamp pad composed of a minimum of parts which may be readily and conveniently assembled or dismantled when desired. In its assembled position the pad 10 elements are maintained against displacement by the resilient and yielding action of its supporting base due to the nature and configuration of the latter. The peculiar and novel construction of the resilient base renders the pad readily yieldable or distortable 15 for the purpose of inserting or releasing the pad member while yet combining the advantages of firmness and rigidity when the pad is in use. 20 A further object is to provide a stamp pad which may be economically manufactured and which constitutes marked improvements over pads of the same general character which are now in use. 25 With such objects in view, as well as other advantages which may be incident to the use of the improvements, the invention consists in the parts and combinations thereof herein-after set forth and claimed, with the understanding that the several necessary elements 30 constituting the same may be varied in proportions and arrangement without departing from the nature and scope of the invention.

In order to make the invention more clearly understood there are shown in the accompanying drawings means for carrying the same into practical effect, without limiting the improvements in their useful applications, to the particular constructions which, 35 for the purpose of explanation, have been made the subject of illustration.

In said drawings:—

Fig. 1 is a plan view of a resilient stamp pad constituting a preferred embodiment of 40 the invention.

Fig. 2 is a side view with the removable slip cover member shown in vertical section.

Fig. 3, a longitudinal vertical section on line 3—3 of Fig. 1.

Fig. 4, a similar view of the resilient base 50 portion of the pad.

Fig. 5 is a fragmentary detail sectional view in which the top of the ink applying pad member is positioned below the top of the resilient base member to provide a more pronounced V-shaped marginal chamber for receiving any surplus ink from the surface of the pad, from which marginal chamber the ink is absorbed by the pad member. 55

Referring to the drawings, the frame or 60 base of the pad is indicated at 1 and is constructed of resilient material such as relatively soft vulcanized rubber. The base is illustrated as of rectangular configuration, but it will be understood that the same may 65 be made square or round or possess any other configuration, if desired. As best seen in Figs. 1 and 4 the resilient base or frame is molded in one piece and is provided with a central aperture 2 of substantially the configuration of the base member and which extends entirely therethrough. A peripheral recess or groove 3 is provided in the base and is suitably spaced between the top and bottom walls thereof. Said recess is preferably 70 continuous and extends entirely around the resilient base member 1 as will be best seen in Figs. 1 and 4. The resilient member or frame is further provided on its top face with an inwardly projecting pad-retaining 75 flange or shoulder 4, formed integrally with the base member and which flange overhangs the aperture 2 and is preferably continuous in extent around the entire periphery of the base. If desired, a continuous recess 80 5 may be provided on the under surface of the resilient base member, or a plurality of such recesses may be employed, to form air cushions and to generally facilitate the use 85 of the stamp pad on a flat surface. The pro- 90

vision, however, of the recess or recesses 5 is not essential in the present improvements and the pad functions just as effectively without such additional cushioning provision.

5 A flat base plate 6 of metal or other preferably rigid material is designed to be inserted within the continuous recess 3. The base plate is constructed of substantially the thickness and depth of the recess, and when 10 inserted within the resilient base or frame member, serves as a rigid closure and pad-supporting member fitting closely at all points against the inner walls of the recess or groove 3 entirely around the periphery of 15 the resilient member 1. A pad member 7 is provided and may be of any well known and desired construction. The overall dimensions of the pad member are substantially the same as those of the aperture 2 of the base member as will be best seen in Fig. 3. 20 As illustrated the pad member comprises an inner filling 8 of felt or other ink absorbing material and a protective enclosing covering 9 of cloth or linen through which the ink contained within the filling may be transmitted to a stamp or article to be inked. The pad member is further illustrated as having a lower reinforcing plate 10 also of substantially the dimensions of the aperture 2, which 25 plate may be of sheet metal to aid in maintaining and preserving the configuration of the pad member of which it constitutes a part. The pad member is provided with a continuous peripheral shoulder 11 which 30 cooperates with the inwardly projecting flange or shoulder 4 of the resilient base member to maintain the pad against vertical displacement after the elements have been assembled.

40 If desired the device may include a removable protecting slip cover 12 of sheet metal or other appropriate material and which when applied engages the marginal shoulder 12a of the base member, as shown in Figs. 2 and 5.

The assembly of the described members of the stamp pad is very simple and convenient. The pad member 7 is placed in position against one side of the base plate 6 and these 50 elements are inserted upwardly from the bottom through the aperture 2 of the resilient retaining member or frame 1. The presence of the central aperture 2 extending entirely through the resilient member 1 together with 55 the yieldable nature of the latter, permits the same to be easily distorted and stretched along any portion of its periphery or radially from its center to accommodate the base plate 6 within the continuous recess or groove 60 3 of the base member. When the plate has been thus positioned the pad member projects upwardly through the upper portion of the central aperture 2 and its shoulder 11 contacts beneath the inturned peripheral flange 65 4 of the base member to insure against fur-

ther upward displacement of the pad. The pad is now ready for use and affords a rigid and yet resilient inking surface for a stamp to be impressed thereon. The pressure of a stamp on the upper surface of the pad results in the member 1 being forced angularly inwardly to more firmly grip the pad due to the cooperation and relation therewith of the rigid base plate 6.

The arrangement is such that when assembled, a V-shaped marginal recess or chamber is formed between the pad member and the shoulder 4 of the base member. Any surplus of ink exuding from the freshly inked pad will collect in this V-shaped recess, without accumulating on the top surface of the resilient member 1, and from said recess the surplus ink is absorbed by the pad and again distributed to the upper surface thereof.

In Fig. 5 the described marginal recess is 85 made more pronounced by extending the interior wall of the flange or shoulder 4 upward to above the top surface of the pad member 8. In this figure the V-shaped marginal recess is shown at 4a and the clearance between the top of the base member and the top of the pad is indicated at 4b.

The operation of dismantling the pad is just as simple and is accomplished by merely stretching or distorting outwardly the walls 25 of the resilient portion 1 to release the base plate 6 from the retaining recess or groove 3 and to permit its removal with the pad 7 through the bottom of the aperture 2.

The construction described results in the 100 provision of an improved and efficient stamp pad, composed of a minimum number of parts and which may be readily and conveniently dismantled and assembled when it is desired to replenish or renew the ink retaining pad 105 member.

What I claim is:—

1. A stamp pad comprising a resilient and radially stretchable frame open from top to bottom, said frame having an inwardly extending continuous flange, a continuous recess in said frame, a rigid plate having its marginal edges disposed in said recess, an ink-applying member supported by said plate and maintained against upward displacement by said continuous flange, and a marginal recess provided between said continuous flange of the frame and said ink-applying member for collecting surplus ink and redistributing it to said ink-applying member.

2. In a stamp pad the combination of a radially stretchable frame open from top to bottom, said frame having a groove in its inner periphery, the upper portion of said frame having an inwardly extending flange, a pad-supporting plate in said groove, and a pad held on said plate and under said flange.

3. A resilient and radially stretchable frame for inking pads open from top to bot-

tom and having on its inner face a groove for the reception and holding of an element of an inking pad.

4. A resilient and radially stretchable frame for inking pads open from top to bottom and having on its inner face a groove and an inwardly extending flange spaced vertically therefrom, said groove and flange being adapted to hold therebetween the elements of an inking pad.

10 In testimony whereof, I affix my signature.
EMANUEL BAUMGARTEN.
